UNITED STATES PATENT OFFICE.

HOMER B. JOHNSON, OF SHERIDAN, INDIANA; EMMA K. JOHNSON, ADMINISTRATRIX OF SAID HOMER B. JOHNSON, DECEASED, ASSIGNOR BY CONSENT OF COURT TO EMMA K. JOHNSON.

APPARATUS FOR CHARGING BEVERAGES.

Application filed March 21, 1923. Serial No. 626,589.

This invention relates to apparatus for use in the manufacture of beverages, such as orange-ade, grape-juice, and root beer, and for recoloring or reflavoring the same. These 5 beverages are not stable compounds, but lose their color and flavor quickly, especially when exposed to light. It is then necessary to inject coloring and flavoring fluid into the bottled beverage, and the primary object 10 of my invention is to provide a simple, compact and efficient mechanism whereby the several operations of decapping, charging, and recapping the bottle may be successively and rapidly performed with a minimum 15 amount of hand labor. Secondary objects of the invention are to provide simple means to regulate the quantity of coloring or flavoring liquid injected into the drink, and to provide means for adjusting the apparatus 20 to the height of the bottle and properly centering the bottle or other receptacle. Other incidental objects of the invention will appear in the course of the following description.

25 The invention is illustrated in the accompanying drawings, in which—

Figure 1 is a front elevation of a machine embodying my present improvements;

Figure 2 is a similar view with some of 30 the parts in a different position;

Figure 3 is a vertical section of the machine;

Figure 4 is a detail showing a supplemental bottle-supporting base.

35 In carrying out my invention, I employ a frame which is adapted to be clamped to the edge of a work table or bench and, in the present instance, comprises a base plate 1 having a jaw 2 connected therewith by hauger arms 3, the said arms being adapted 40 to extend across the edge of the table, 4, and a set screw 5 being mounted in the jaw 2 to bear against the under side of the table and thereby clamp the frame in the working 45 position. On the upper side of the base 1, at the ends of the same, are sockets 6 receiving the lower ends of standards 7 which are connected at their upper ends by a head 50 or yoke 8, the whole assembly constituting a rigid upright frame.

Extending between the standards is a holding bridge consisting of a bar 9 having sleeves 10 at its ends which are slidably fitted upon the standards, the bar being provided centrally with an opening 11 in which the 55 neck of the bottle or other receptacle 12 is received. A bar 13 rises from the base adjacent one standard 7 and is provided along its upper portion with notches 14 which may conveniently be formed by threading the rod. 60 A latch 140 is pivotally supported below the bridge 9 in position to engage the notches 14 and a presser bar 141 is pivoted to the free end of the latch and rises therefrom through the bridge, a head 142 being provided on 65 the upper end of the presser bar and a spring 143 being coiled around the presser bar between the bridge and the head. Springs 144 are coiled around the standards between the 70 sockets 6 and the bridge and furnish yieldable supports for the bridge, tending constantly to hold it in an upper position. The bottle to be filled or charged is placed upon the base 1 and the bridge is slid down into engagement therewith, the latch riding over 75 the notches until the downward movement of the bridge is arrested by its engagement with the neck of the bottle whereupon the latch will engage the notch 14 presented thereto and prevent premature upward movement of the bridge. It will be readily seen 80 that the mouth of the bottle will project above the bridge and the bridge will be automatically adjusted to the height of the bottle. When the bottle has been charged, a slight 85 pressure on the head 142 will release the latch so that the bridge may be raised under the influence of the springs 144 and the bottle removed.

If short bottles are to be filled or charged, 90 a supplemental base or seat 145 may be employed. This seat comprises a plate having a marginal raised flange or rim 146 at its front edge portion and carried by a post 147 which is screwed into the base 1 so that 95 it may be easily inserted or removed.

The head or yoke 8 is constructed with a central vertical tubular member or guide 15 in the upper extremity of which is fitted a stop plug 16. A hollow plunger 17 is fitted 100

snugly but slidably in the lower portion of the guide 15 and extends through and below the lower end thereof, an expanded hollow head or sealing cup 18 being carried by the 5 lower end of the plunger. Upon the plunger is a collar 19 consisting of mating members secured together and around the plunger, and a decapper lever 20 is pivotally secured upon one end of said collar. The decapper 10 extends below the head 18 and is provided with a tooth or hook 21 at its lower end which is adapted to engage under the edge of the cap 22 which is to be removed from the bottle. The under side of the hook or 15 tooth is beveled, as shown, so that it may readily ride downwardly over the side of the cap, and an expansion spring 23 is fitted between the side of the plunger and the upper end of the decapper to yieldably hold 20 the lower working end of the decapper in operative position. An operating lever or handle 24 is fulcrumed on one of the standards 7 and, at its inner end, has a pin and slot connection with the plunger, as shown 25 at 25, the lever being preferably forked so as to span the standard and the plunger and thereby obtain a well balanced and even motion. It will be readily understood that when the outer free end of the lever 24 is 30 raised, the inner end thereof, with the plunger and decapper, will be lowered so that the decapper will engage under the cap and will lift the same from the bottle with the ensuing upward movement of the plunger 35 and lever. Studs 148 may be provided on the base to prevent the bottle sliding sideways when being decapped.

The operating lever may be fulcrumed directly upon the standard, but to reinforce 40 and strengthen the standard I provide an enlargement 26 to carry the fulcrum and from the lower end of this enlargement, a bracket arm 27 extends downwardly and outwardly to carry the pump 28 which may 45 be of the usual form and is illustrated in a conventional manner only. The inlet 29 is connected with a reservoir or source of supply (not shown) and a hose or flexible pipe 30 leads from the outlet 31 of the pump to 50 deliver the liquid to the bottle, as will be presently fully set forth. The plunger 32 of the pump plays through the upper end of the pump body and is in the vertical plane of the operating lever so that it may be engaged and depressed by the lever, a roller 33 being mounted on the under side of the lever to ride upon the upper end of the plunger and thereby minimize the frictional resistance and wear. The plunger is normally 55 held in its raised position by a spring 34 coiled around the plunger between the upper end of the pump body and a flange 35 at the upper end of the plunger. From the said flange, a guide and stop rod 36 depends 60 through a lug or eye 37 on the pump sup-

port, and a nut 38 is fitted on the lower end of this rod to abut the under side of said lug or eye and thereby limit the upward movement of the plunger. The stroke of the pump can thus be readily regulated so 70 that the desired quantity of the liquid will be discharged. This regulation of the stroke of the pump is important as it insures the supply of a fixed measured amount of liquid on each stroke of the pump with resulting 75 uniform quality in the product. It is usual, in the manufacture of the beverages, to combine the flavoring material or extract with the desired kind and amount of coloring material, and a predetermined amount of 80 this mixture, carefully measured, is injected into the bottle which has already been filled with the proper amount of the simple syrup, carbonated water, fruit juices, or other material which constitutes the main body of the 85 drink.

The hose or flexible pipe 30 terminates in a nozzle 39 which, when in use, is situated below the plunger 17 and directly over the mouth of the bottle so that the liquid issuing 90 from the nozzle will pass into the bottle. The nozzle must be moved out of the way of the plunger when the plunger is descending, and the machine embodies means for that purpose which I will now describe. The 95 nozzle is carried by the lower end of a rocking arm 40 which is mounted on the back of the frame in the same transverse vertical plane as the plunger 17, a convenient support being a bracket 41 projecting from the 100 lower end of the head or yoke 8 and to which the rocking arm is pivoted near its upper end. An expansion spring 42 is secured to and arranged between the upper end of the rocking arm and the rear side of the yoke or 105 head 8 and tends constantly to hold the lower end of the arm toward the plunger and the nozzle, therefore, over the bottle. Below its pivot, the rocking arm is provided with a cam or beveled offset 43 arranged to 110 be engaged by a projection 44 on the plunger which may very conveniently be one end of the pin connecting the lever 24 to the plunger. As the plunger is lowered, the projection 44 rides on the upper incline of the offset 43 and throws the rocking arm out so 115 that the nozzle is carried to the rear of the plunger, and the offset is preferably, just a trifle longer than the stroke of the plunger so that its engagement with the projection 120 44 holds the nozzle retracted until the plunger begins to ascend. Upon the ascent of the plunger, the spring 42 will be free to act and the rocking arm will return to its normal position, the nozzle locating itself 125 over the mouth of the bottle immediately after the decapping and just before the working stroke of the pump plunger starts.

It is, of course, necessary to recap the 130 bottle. To accomplish this result, the bottle

cap is placed in the sealing cup or head 18 against the end of the magnetized rod 45 which is snugly but slidably fitted in the lower portion of the plunger 17. The 5 plunger is then moved downward and forces the cap on the bottle, the nozzle, of course, being again retracted. To prevent the decapper from pulling off the just applied cap, the rod 45 is provided with a pin or projection 46 playing in a slot 47 in the plunger 10 to ride upon a cam projection 48 on the decapper. The movement of the rod 45 within the plunger is limited by the pin 46 impacting against the ends of the slot 47, and 15 a coiled spring 49, disposed within the plunger between the upper end of the rod 45 and the plug 50 which is mounted in the upper end of the plunger and rests on the spring 49, holds the rod yieldably in its 20 lowered position. The cap is placed against the end of the rod 45 and the cap 18, partially entering the cap, whereupon the lever 24 is again swung upwardly so that the plunger and the rod therein will be again 25 lowered and the cap placed in proper position on the bottle. The resistance offered by the cap and the bottle causes the rod 45 to move relatively upward while the plunger and cup complete the downward movement, 30 the edge of the cap 18 riding on the flange of the cap and compressing the same around the bottle. As the rod 45 moves relatively upward, the pin 46 thereon rides against the cam offset 48 on the decapper lever 20 35 and rocks the lever against the tension of the spring 23, the movement ceasing while the pin is between the ends of the offset. Consequently, the decapper hook will be swung away from the newly applied cap. The 40 spring 49 is balanced between the rod 45 and the plug 50 and the relative upward movement of the rod is therefore imparted to the plug so that the upper position of the rod and the inoperative position of the decapper will be maintained during the ensuing up stroke of the plunger. The upward movement thus given the plug 50 raises it 45 above its normal position so that the completion of the up stroke of the plunger will 50 carry the plug 50 against the fixed stop plug 16 whereby the plug 50 will be returned to its normal position in the plunger, compressing the spring 49 which will, in turn, thereupon lower the rod 45 to its normal 55 position. This relative downward movement of the rod 45, of course, carries the pin 46 of the cam 48 and permits the decapper to return to active position, thus setting the 60 parts for a repetition of the operating cycle. To magnetize the rod 45 and the plunger, I provide a battery 150 which is supported on the head 8, and a coil 151 which is mounted on and encircles the plunger 17 just below the end of the operating lever 24. One 65 terminal of the coil is connected to the plunger, as at 152, and the other terminal of the coil is attached to the contact or switch member 153 which is mounted on the side of the plunger and insulated therefrom; it being noted that the contact 153 is in the 70 form of an upwardly extending plate having its upper end turned outwardly as shown. One terminal of the battery is grounded on the frame of the machine, as at 154, while the other terminal is connected by a lead 155 with the upper end of a contact plate or switch member 156 which is secured to and depends from the under side of the head 8 but is insulated therefrom. It will be noted that the contact plate 156 extends 75 downwardly past but close to the contact 153 and that it is formed with an offset or shoulder 157 projecting into the path of the outturned upper end of said contact 153. When the plunger moves downwardly, in 80 the capping action, the end of the contact 153 is carried against the shoulder 157 and the circuit is closed thereby magnetizing the plunger and the capper rod so that they will 85 magnetically hold the cap and it will not be necessary for the operator to place the cap on the bottle and expose his fingers to injury. To enlarge the sphere of usefulness of the 90 machine, I have provided a nozzle 51 to deliver the body or base liquid (simple syrup, carbonated water, fruit juices, etc.,) to the 95 bottle. The nozzle 51 is carried by a measuring vessel 52 which is mounted on an arm 53 having a hub 54 rotatably encircling the adjacent standard 7, a stud 55 on the standard 100 engaging a circumferentially extending slot 56 in the arm to prevent dropping of the arm and arrest the movement of the same when the nozzle is directly over the mouth of the bottle. The end of the nozzle 51 is 105 arranged to impinge upon the nozzle 39 and push it out of the way. The nozzle 51 is fitted to the end of a hose 57 leading from a source of supply, and is equipped with a two-way cut-off valve 58 controlled by a 110 hand lever 59 at one end. The nozzle is constructed with a branch 60 leading to and united with the bottom of the vessel 52, and the valve is located at the junction of 115 said branch with the main body of the nozzle. When set in the position shown, the valve establishes communication between the 120 hose and the vessel or tank 52 but if it be given a quarter turn, communication between the tank and the outlet side of the 125 nozzle will be established, flow from the hose being cut off. Within the branch 60 is a valve 61 which is adapted to seat against and close the port 62 in the bottom of the vessel and the stem 63 of which extends through 130 the said port and through the top of the measuring vessel. Within the tank or measuring vessel is a float 64 having a central opening therethrough, and a tube 65 rises from the float through the top of the vessel.

The valve stem 63 passes loosely through the float and the said tube, and a set screw 66 in the upper end of the tube bears against the stem to adjustably secure the float thereon, 5 so that it may be set to admit any desired quantity of water to the tank. With the valve 58 in the position shown, discharge from the nozzle is cut off and water may enter the tank or measuring vessel until it 10 lifts the float to such a height that the valve 61 is seated. When a bottle is to be filled, the arm 53 is swung around to bring the nozzle 51 over the bottle after which the handle 59 is rocked through one-quarter of 15 a turn so that the valve 58 will block flow from the hose but permit flow from the tank. After the contents of the tank have been discharged, the parts are returned to initial position and another measured quantity of liquid permitted to enter the tank 20 while the processes of coloring or flavoring the liquid and capping the bottle are performed.

The body of soft drinks is usually of plain 25 or carbonated water which, in my apparatus, is supplied in measured quantities through the measuring vessel or tank 52. To this body is added an exact quantity of a combination of concentrated flavoring extract, 30 coloring matter, and simple syrup, which combination is supplied through the plunger pump. The apparatus can be used in the original manufacture of the beverage or to recharge a beverage which has lost its color 35 or flavor.

Having fully described my invention what I claim as new and desire to secure by Letters-Patent, is:—

1. In a bottle-charging machine, the combination of a base upon which a bottle may 40 be stood, standards rising from the base, a locking bar rising from the base and having a series of notches in its side, a bridge slidably mounted on said standards to engage 45 and hold the bottle placed on the base, and a latch carried by the bridge to engage any one of the notches in the locking bar and hold the bridge in a set position.

2. In a bottle-charging machine, the combination of a nozzle to deliver liquid to a 50 bottle, a capper movable toward and from the bottle, the nozzle being disposed between the capper and the bottle when in operative position, and means controlled by 55 the capper for moving the nozzle laterally from over the bottle as the capper approaches and return it as the capper recedes.

3. In a bottle-charging machine, the combination of a frame, means for sustaining a 60 bottle thereon, a plunger mounted on the frame above the bottle-sustaining means and movable toward and from the same, a bottle-capper carried by the plunger, a decapper carried by the plunger, and means

whereby the decapper will be rendered in- 65 operative during operation of the capper.

4. In a bottle-charging machine, the combination of bottle-sustaining means, means for delivering liquid to a bottle held in said means including a nozzle normally positioned over the bottle, a rocking arm carrying the nozzle, a cam on said arm, yieldable means acting on said arm to hold the nozzle in normal position, a plunger movable toward or from the bottle, and a projection 70 on the plunger arranged to engage the cam on the rocking arm whereby upon descent of the plunger the nozzle will be moved aside.

5. In a bottle-charging machine, the combination of bottle-sustaining means, a plunger movable toward and from said means, a decapper lever mounted on and extending below the plunger, a cam projection on said lever presented toward the plunger, a rod 85 slidable in the plunger, and means on the rod to engage the cam projection on the decapper lever and move said lever to inoperative position when the plunger is actuated 90 to apply a cap.

6. In a bottle-charging machine, the combination of bottle sustaining means, means for delivering liquid into the bottle including a nozzle located normally over the bottle, a plunger movable toward and from the 95 bottle, a sealing cup on the lower end of the plunger, a rod in the plunger adapted to support a bottle cap in the lower end of the sealing cup, and means actuated by the plunger to move the nozzle aside as the 100 plunger approaches the bottle.

7. In a bottle-charging machine, the combination of bottle-sustaining means, means for delivering liquid into the bottle including a nozzle located normally over the bottle, a plunger movable toward and from the bottle, a sealing cup on the lower end of the plunger, a magnetized rod in the plunger adapted to support a bottle cap in the lower 105 end of the sealing cup, and means carried 110 by the plunger to move the nozzle aside as the plunger approaches the bottle.

8. In a bottle-charging machine, the combination of bottle-sustaining means, a hollow plunger mounted above said means to move to and from a sustained bottle, said plunger having a longitudinal slot in its side, a decapper lever pivoted on the plunger and projecting below the same and having a cam projection on its side presented 115 to the slot in the plunger, a plug closing the slot in the plunger, a rod fitted in the upper end of the plunger, a pin on said rod projecting through the slot in the plunger 120 to engage the cam projection on the decapper lever, and an expansion spring within 125 the plunger between and bearing against the plug and the rod.

9. In a bottle-charging machine, the combination of a supporting frame, bottle-sustaining means thereon, a charging nozzle, a swinging support for said nozzle, a filling nozzle, and a swinging support for the filling nozzle, the nozzle supports being at opposite sides of the bottle-sustaining means and the nozzles being in the same horizontal plane whereby the charging nozzle will be moved aside by the filling nozzle as the latter is brought into position over a bottle held in the sustaining means. 10

In testimony whereof, I have signed this specification.

HOMER B. JOHNSON.
